UNITED STATES PATENT OFFICE.

EDWARD BEAR, OF NEW YORK, N. Y.

CLOTHESLINE FASTENER.

Application filed March 16, 1922. Serial No. 544,295.

To all whom it may concern:

Be it known that I, EDWARD BEAR, a citizen of the United States, residing at Bronx, county of Bronx, and State of New York, 5 have invented certain new and useful Improvements in a Clothesline Fastener, of which the following is a specification.

This invention relates to improvements in clothes line adjusters, and it is the principal object of the invention to provide a device of this character which will allow a ready and convenient adjustment of any slack in the line and effectively prevent the parting of a line which is accidentally 15 dropped.

Another object of the invention is the provision of a device which is extremely simple in its construction and therefore inexpensive to manufacture and extremely convenient to operate.

These and other objects and advantages of my device will become more fully apparent as the description thereof proceeds, and will then be specifically pointed out in the 25 appended claim.

In the accompanying drawing, forming a material part of this invention:

Figure 1 is a diagrammatic view showing the device connected with a clothes line.

Figure 2 is a front view of my device on an enlarged scale seen along line 2-2 of Figure 3, and

Figure 3 is an end view of my device.

The device comprises a body, preferably 35 of metal, bent upon itself to form a member 10 of substantial U-shaped cross section to provide shanks 11 and 12 spaced from each other, and the inner bottom wall of member 10 is corrugated as indicated at 13.

40 A pin 14 is passed transversely through shanks 11 and 12 at a distance above the

bottom of member 10 and on this pin a toothed segment 15 is pivotally secured, having a flat part 16 on its lower face. Integral with segment 15 is a handle 17 provided with openings 18 and 19.

A clothes line 20 is guided over pulleys 21 and 22 secured in the usual manner by means of their eyes 23 to hooks 24 fastened to any suitable supporting means.

One of the ends of line 20 is guided through clamp member 10 as indicated at 25 while the other end of said line is guided through opening 18 and formed behind the same into a knot 25.

The operation of my device will be clear without further explanation from the above description.

Changes may be made in the general arrangement of parts and the construction of 60 the minor details without departing from the scope and spirit of my invention.

What I claim as new, and desire to secure by Letters Patent of the United States is:—

A device of the class described comprising 65 a body member formed by bending its material upon itself to form parallel shanks in spaced relation to each other, corrugations on the inner bottom wall of said member adapted to engage one end of a clothes 70 line, a transverse pin in said body member, a toothed segment pivotally secured to said pin and having a flat face separating its tooth parts at its bottom part, and a perforated handle formed with said segment 75 for allowing the passage of the other end of said line adapted to be held against said handle by a knot formed in said end after its passage through said handle.

In testimony whereof I have affixed my 80 signature.

EDWARD BEAR.
